UNITED STATES PATENT OFFICE.

EMANUEL W. HARTMAN, OF OAKLAND, CALIFORNIA, ASSIGNOR TO CALIFORNIA BUILDING MATERIAL COMPANY, OF SAN FRANCISCO, CALIFORNIA, A CORPORATION OF CALIFORNIA.

HEAD-COLLAR FOR PILES.

1,059,461.

Specification of Letters Patent. Patented Apr. 22, 1913.

Application filed January 31, 1912, Serial No. 674,444.

To all whom it may concern:

Be it known that I, EMANUEL W. HARTMAN, a citizen of the United States, residing at Oakland, in the county of Alameda and State of California, have invented certain new and useful Improvements in Head-Collars for Piles, of which the following is a specification.

My invention relates to the class of collars or rings for the heads or upper ends of piles.

The objects of the invention are to steady and guide the head of the pile while being driven, and also to protect it from injury under the blows of the hammer.

Though my invention is applicable to piles of various materials and constructions, particularly in its steadyng and guiding function, it is especially useful for and is intended for application to concrete piles, in that it affords the necessary protection against injury from blows.

My invention consists in the novel collar, which I shall now fully describe by reference to the accompanying drawings, in which—

Figure 1 is a plan, showing the application of the collar. Fig. 2 is a vertical section of the same. Fig. 3 is a bottom view of the collar.

1, in Fig. 2, is the head of a pile. This pile may be of any material or construction. In the best use of my invention the pile is of concrete, the head being polygonal and tapering.

2 is the collar. It is best made of cast-steel. Its inner surface is tapered from the lower side upwardly, as shown at 3, and is formed with sides corresponding to the sides of the pile head, so that it will fit down upon, closely embrace and be supported by said head. The taper of the inner surface of the collar extends only part way through, and thence to the top said surface is straight and forms a chamber or socket 4, above the top of the pile. In this socket is placed and held the striking block 5 which rests upon

the top of the pile, and through a hammer plate 6 receives the blows of the hammer. The collar 2 is formed with side grooves 7 which fit and slide upon the leads or guides 8 of the pile driver frame.

It will now be seen that the collar 2, by fitting both the pile head and the guides 8 of the pile driver frame, serves to steady and guide the pile, while being driven. The principal function, however, of the collar is to protect the head of the pile from injury resulting from the hammer blows, which function it performs by taking upon itself the circumferential tension due to the blows. By projecting above the pile head, the collar forms a socket to receive and hold the striking block, which it also protects by its circumferential tension.

Having thus described my invention what I claim as new and desire to secure by Letters Patent is—

In a device of the character described, a head collar comprising a solid portion having an opening therethrough, the lower portion of which is tapered to fit upon and closely embrace the upper end of a correspondingly shaped pile, the upper portion of which is provided with a vertically disposed wall to provide a socket in the upper portion of the head collar when the same is in position upon a pile, and a striking block positioned within and completely filling the socket in said head collar, said striking block extending above the upper surface of the head collar and the lower portion thereof being positioned to directly engage the top of the pile.

In testimony whereof I have signed my name to this specification in the presence of two subscribing witnesses.

EMANUEL W. HARTMAN.
